HOIST LINE HOOK

Herbert E. Grau, Huntington Park, Calif., assignor to Byron Jackson Co., Huntington Park, Calif., a corporation of Delaware

Application May 6, 1936, Serial No. 78,186

3 Claims. (Cl. 294—82)

This invention relates to hoist line hooks such as are employed for raising and lowering drill pipe tubing or casing in an oil well. More particularly, the invention relates to improvements 5 in that type of hook which is provided with a safety latch for closing the entrance to the hook. One such type of drill pipe and casing is illustrated in U. S. Patent No. 1,825,018 issued September 29, 1931 to Nelson K. Smith. Two 10 such types of tubing hooks are illustrated in U. S. Patent No. 2,027,376, issued January 14, 1936 to Herbert E. Grau.

Hoist line hooks for oil well service as constructed heretofore are provided with a downwardly and inwardly (toward the vertical axis of the hook shank) bail-receiving notch, a pivoted arm for closing the entrance to the notch and a releasable lock for the closing arm. The closing arm, when in the closed position, extends 20 upwardly and inwardly toward the shank axis so that the upper end of the closing arm is above the bail in the notch. If the hook should be subjected to a violent jar in a vertical direction, such as might occur if the drilling line should 25 break, the bail will spring upwardly and strike the closing arm a sharp blow which might be sufficient to break the locking mechanism. It is obvious that space limitations will not permit the lock to be made large enough to withstand the 30 most violent blows.

It is the object of the present invention to provide guard means for preventing the bail from striking the closing arm more than a glancing blow which would be insufficient to cause damage.

In the drawing:

Figure 1 is a vertical side elevation, partly in cross section, taken on line B—B of Figure 2, showing a safety hook provided with my novel 40 guard means.

Figure 2 is a vertical front elevation, partly in cross section, taken on line A—A of Figure 1.

Inasmuch as my invention is concerned only 45 with the bail-receiving portion of the hook and has nothing to do with the swivelling mechanism or supporting becket I have shown only the lower portion of a hook in the drawing. The hook body is designated at 1 and is, in the present instance, (though not necessarily), supported from a cross 50 pin 3 secured to a shank 5. The hook body is provided with a forwardly extending bill 7 forming a bail-receiving notch 9. A bail is indicated in the notch as shown at 11. A notch closing arm 13 is pivotally connected to the end of bill 7 by 55 means of a pin 15. The closing arm 13 is

adapted, when in the closed position, to extend upwardly and somewhat inwardly toward the shank axis so as to close the entrance to the bail-receiving notch 9. The upper end or head 16 of the closing arm 13 is, in the present instance, 5 adapted to engage a lug 14 formed on the body 1 so as to carry a part of the load. The closing arm is also provided with latching means for locking the arm in the closed position. In the present instance the latch comprises a vertically 10 sliding latch bolt 17 supported on a coil compression spring 19. The closing arm 13 is provided with an inwardly extending finger 18 adapted to be engaged by the bail 11 to insure that the closing arm will be fully closed and 15 locked when under load. The latch and lock construction shown herein are merely illustrative of one form of latch which may be used with hooks of the type in question.

In order to prevent the bail 11 from striking 20 the closing arm 13 a direct blow sufficient to break the latch 17 I provide a bumper recess 21 in the under side of the hook body at the top of the bail-receiving notch 9. The bumper recess 21 is positioned substantially directly above the 25 bottom of the bail-receiving notch 9 and in line with the vertical axis of the hook shank. The bumper recess 21 is preferably concave, being curved in the plane shown in Figure 2 to conform approximately to the curvature of the bight 30 of the bail 11, and being curved as shown in Figure 1 to conform substantially to the top of the bail as shown in the plane of Figure 1. The forward end of the bumper recess is preferably extended downwardly a substantial distance, sufficient 35 to form an overhanging guard or abutment 23 which will tend to force the bail back into the recess 21 away from the closing arm 13.

In hoist line hooks for oil well use the bail-receiving notch 9 is made as small as possible, 40 being not substantially larger than the bail or bails normally received therein. I form the bumper recess 21 as substantially a complement to the size and shape of the lower portion of the bail-receiving notch 9 so that the bail or bails 45 will be received wholly within the recess 21 in the event of an upward jar.

I claim:

1. In a hoist line hook having a body with a forwardly extending bill forming a bail-receiving 50 notch extending inwardly and downwardly toward the vertical axis of the hook, latch means adapted to close the entrance to said bail-receiving notch, said hook body having a concave bumper recess formed in its under side adjacent 55

the top of said bail-receiving notch and substantially in line with the vertical axis of the hook, said bumper recess being curved to conform substantially to the shape of the bight of a bail.

5. 2. In a hoist line safety hook having a body with a forwardly extending bill forming a bail-receiving notch extending inwardly and downwardly toward the vertical axis of the hook, an 10 arm pivotally mounted on said hook body and adapted to close the entrance to said bail-receiving notch, a latch for releasably securing said arm in the closed position, said hook body having a concave bumper recess formed in its under 15 side adjacent the top of said bail-receiving notch and substantially in line with the vertical axis of the hook, said bumper recess being curved to conform substantially to the shape of the bight of a bail.

3. In a hoist line safety hook having a body with a forwardly extending bill forming a bail-receiving notch extending inwardly and downwardly toward the vertical axis of the hook, an 5 arm pivotally mounted on said body and adapted to close the entrance to said bail-receiving notch, a latch for releasably securing said arm in the closed position, said hook body having a bumper recess formed in its under side adjacent the top of said bail-receiving notch and substantially in 10 line with the vertical axis of the hook, said bumper recess having its forward wall extending outwardly and downwardly away from the axis of the hook a distance sufficient to form a deflecting guard wall for a bail, and being forward of the 15 position normally occupied by a bail.

HERBERT E. GRAU.
